UNITED STATES PATENT OFFICE

WILFORD E. BURNS, OF BURLINGAME, CALIFORNIA, ASSIGNOR TO M. J. B. CO., OF SAN FRANCISCO, CALIFORNIA, A CORPORATION OF DELAWARE

CAN

Application filed March 7, 1927. Serial No. 173,460.

This invention relates to the so-called tin cans as used for preserving food and has to do with special construction in a can of the tearing strip removable end type of can as shown in my U. S. Patent No. 1,615,930 issued on February 1, 1927.

The objects of the present invention are to effect improvements in a can of the character described whereby less bending of the metal is required, the seams will be more durable and the can may be manufactured easily.

In the drawing hereto my improved can is shown in elevation in Fig. 1 with portion of its front wall broken away to show the internal construction. Fig. 2 shows in somewhat enlarged cross section the outwardly displaced vertical lock seam as seen from the line 2—2 of Fig. 1. Fig. 3 is a cross section of the upper portion of the can enlarged about five times to illustrate better the form and relation of its parts. Fig. 4 shows in broken plan the full size of the special notching and slitting of the can body blank. Fig. 5 shows the blank folded to form a triple layer across the upper end preparatory to forming the tubular body. Fig. 6 is a vertical section of Fig. 5 taken along the line 6—6 thereof, and Fig. 7 shows the ends of the folded blank of Fig. 5 brought together and joined by a compound lock, butt, and lap seam.

In further detail the can comprises a tubular body 1 of sheet metal with lower and upper heads 2 and 3 respectively double seamed or crimped thereto, as indicated.

The body of this can is of constant internal diameter across the various points as at A, B, C, or rather has a smooth unbroken wall from top to bottom for it is obvious that it may be tapered, or may even be a rectangular can in so far as the present invention is concerned.

At the upper end the body metal is folded outwardly and downwardly upon itself and then upward, (all done before forming the blank into a tube) so as to provide a triple layer or band of metal at the upper end and the outer layer 4 of which is circumferentially scored at the points D—E to provide a tearing strip and which terminates in a free tongue 5 in the known manner so that

it may be engaged by a key and torn off, and thereby leaving the top end or lid of the can free.

This top end it will be observed has a plain or slightly curved annular wall 6 descending into the can interior and fitting snugly against the doubled-over rounded upper edge 1' of the can body so as to form an internal friction lid therefor when the tearing strip is torn off.

Such lids which are released upon tearing off a circumferential strip from the can body are not new, in fact one is shown in my patent above mentioned, but in the present instance it should be observed that the triple band of metal lies entirely to the outside of the straight inside vertical surface of the can wall, thus there is no inward bending of the metal to form the triple band, and the final outer layer 4 rises with a slight inward bend above the band into the crimp or double seamed joint G formed with the lid member 3.

Some cans of this type in the prior art had an internal ridge or shoulder caused through the inward bending or curving of the body metal to form the triple layer, and as this reduces the internal diameter of the can near the top it is objectional in preventing the ready discharge of some commodities from such cans the importance of a straight interior wall will be evident.

From the lower edge of the triple layer band the body is formed with a lock seam 7 of which the fold lies within the can as is common practice, but in the present can, the multiple band lying outside of the can body forms an external step at X which would prevent machine soldering of the vertical seam (done before flanging the body and seaming on of the heads) and which is one of the reasons why such cans have not come into common use. However, I have found that the body may be so formed as to bring the outside of the vertical seam flush with the outer layer 4 of the band just at the lower edge of the band and then gradually fall back into line with the can wall as designated by the dotted line F.

This is preferably done by the aid of a suitably shaped forming horn when making the

tubular bodies and closing the vertical lock seam, and it effects a pushing out of the seam and adjacent metal a distance equal to two thicknesses of metal at the lower edge of the 5 triple multiple band and thence gradually falling inward to nothing at the bottom. If desired the metal may be given the required offset before locking the vertical seam.

This outwardly angular displacement of 10 the vertical lock seam to a position along the dotted line F would be difficult to represent in vertical section in a Patent Office drawing since the vertical lock seam 7 is of four thicknesses of metal each thinner than a single 15 line of a drawing, but it is sufficiently shown in Fig. 2 a cross section through the outwardly displaced lock seam 7 taken just below the band and showing the outside of the seam displaced outwardly to the point F corresponding to the upper end of line F of Fig. 20 1 or outside surface of the band.

In Fig. 3 the enlarged cross section of the folded body wall of the can and lid double-seamed thereto, shows in dotted lines 3' another lid to illustrate how the lids would nest 25 one upon the other with absolutely no tendency to wedge together. This is due to making the annular depression H of such a shape that while of an outer diameter just large 30 enough to receive another lid, its inner diameter defined by the vertical wall will not permit the annular depressed portion of a lid above to enter. This is very important in facilitating the manufacture of this particu- 35 lar type of can wherein the lids before crimping or seaming to the can-bodies are stacked in the manner indicated and must be proof against sticking together, yet should be self aligning.

40 It might here be mentioned that the slight inward bend of the outermost layer 4 of the can wall observed just above the band is the natural result of forming the body blank to tubular shape as the single wall above the 45 triple layer band being unsupported therefore falls inwardly a trifle at this point.

In making the body of my can I cut out a blank specially notched and slit as shown in Fig. 4, score it on the far side along the 50 lines D, E, and then fold it twice upon itself to the position of parts indicated in Figs. 5 and 6. The margins 15, 16 are reversely hooked as indicated in Fig. 5, and the blank is formed to tubular shape with the margins 55 engaged to produce the vertical lock seam 7 which extends from the lower edge X only of the multiple layer band downward.

60 By observing the blank of Fig. 4 it will be seen that the left hand edge is straight with the exception of the angularly notched out portion 17-18, and that after bending the margin 15 forwardly to form the hook as shown in Fig. 5 that the portions J, K, project beyond the folded edge 15 which in this 65 respect differs from my former patent men-

tioned and provides for a better overlapping joint when the tubular body is joined as in Fig. 7 wherein the relation of portions J, K, are indicated as the innermost layer of metal overlapping the innermost layers of 70 the opposite end of the blank.

The outermost layer 22 of the blank is slightly notched above and below the tearing strip tongue 5 as indicated at 23 so that the strip will start to tear properly, and if desired the scoring of the strip may include the known angularly diverging or herringbone score lines d, e, as indicated on Fig. 1. 75

When the vertical joint is complete the angularly notched portions 17-18-19-20 80 form abutting edges sandwiched between the outermost layer 22 and innermost layer J which lie in simple overlapping relation to the surrounding metal, all as thought clearly shown in Fig. 7.

85 In Fig. 5 the angular edges 18-20 are seen to extend slightly beyond edges 17-19, but in forming the tubular body these all align due to larger diameter of the outer layer.

90 Before soldering the vertical seam it is displaced angularly outward to line F as previously described, and after soldering the vertical seam the ends of the body are flanged outwardly and double seamed to the heads in the usual manner.

95 In considering my can as shown in the drawing it will be observed that after tearing off the strip along the lines D-E the freed internal friction lid is already just seated within the can and is capable, under 100 pressure of a slight further downward movement to insure an air tight friction fit, so that the lid may always be replaced in an air tight manner over the contents until all are used.

105 I claim:

1. A sheet metal can comprising a tubular body with a bottom and a top head secured thereto, said body being folded at its upper end to produce a band of a plurality of layers of metal around the can while preserving a straight internal wall to the can, score lines on the outermost layer of metal defining a tearing strip therearound, and said outermost layer extending upward above said triple layer into engagement with said top head and outwardly flanged and double seamed to said top head.

110 2. A sheet metal can comprising a tubular body with a bottom and a top head secured thereto, said body being folded at its upper end to produce a band of a plurality of layers of metal around the can while preserving a straight internal wall to the can, score lines 115 on the outermost layer of metal defining a tearing strip therearound, said body being joined by a lock seam from the band downward, and said lock seam being displaced outward from the can to substantially flush rela- 120 125 130

tion with the outer surface of said band at its juncture with the same.

3. A sheet metal can comprising a tubular body with a bottom and a top head secured thereto, said body being folded at its upper end to produce a band of plurality of layers of metal around the can while preserving a straight internal wall to the can, score lines on the outermost layer of metal defining a tearing strip therearound; said body being joined by a lock seam from the band downward, and said lock seam being displaced outward from the can to substantially flush relation with the outer surface of said band at its juncture with the same, and falling gradually back into the line of the can body toward the lower end of the can.

4. A sheet metal can comprising a tubular body with a bottom and a top head secured thereto, said body being folded at its upper end to produce a band of a plurality of layers of metal around the can while preserving a straight internal wall to the can, score lines on the outermost layer of metal defining a tearing strip therearound, said body being joined by a lock seam from the band downward, and said lock seam and adjacent metal being displaced outward from the can to substantially flush relation with the outer surface of said band at its juncture with the same and falling gradually back into the line of the can body toward the lower end of the can.

5. A sheet metal can comprising a tubular body with heads secured thereto, the wall of said body being bent outwardly and folded upon itself adjacent one end to produce a multiple layer band of metal around the can, said body being longitudinally seamed and the seam displaced outwardly to substantially flush relation on the outside with the outside of said band.

6. A sheet metal can comprising a tubular body with heads secured thereto, said body provided with an outwardly projecting circumferential step at its upper end, and said body being joined by a vertical seam having an outer surface substantially flush with the outside of said step.

7. A sheet metal can comprising a tubular body with heads secured thereto, the wall of said body adjacent the upper end of the can being folded in reverse directions upon itself to produce a multiple layer band of metal around the can, said body being longitudinally joined by a lock seam from the lower edge of said band downwardly, the body seam at the band comprising intermediate layers of metal with edges in abutting relation sandwiched between layers extending respectively in opposite directions past the abutting edges and one of said last mentioned layers for the width of said band extending substantially past the lock seam of the body.

8. A sheet metal can comprising a tubular body with heads secured thereto, the wall of

said body adjacent the upper end of the can being folded in reverse directions upon itself to produce a multiple layer band of metal around the can, said body being longitudinally joined by a lock seam from the lower edge of said band downwardly, the body seam at the band comprising intermediate layers of metal with edges in abutting relation sandwiched between inner and outer layers of the band extending respectively in opposite directions past the abutting edges and the inner one of said last mentioned layers for the width of said band extending substantially past the lock seam of the body.
